CLAIM

The ornamental design for “single-user swing chair”, as shown and described.

DESCRIPTION

FIG. 1 is a perspective view of “single-user swing chair” showing my new design thereof;

FIG. 2 is a right side elevational view thereof and the left side elevational view being a mirror image thereof;

FIG. 3 is a top plan view thereof;

FIG. 4 is a front side elevational view thereof

FIG. 5 is a bottom plan view thereof,

FIG. 6 is a rear side elevational view thereof; and,

FIG. 7 is a perspective view thereof shown in using position.

The broken line showing of the canopy and the seat in FIG. 7 is for illustrative purposes only and forms no part of the claimed design.
